4 Claims. (Cl. 30—67)

This invention relates to safety razors, and provides a new or improved construction thereof, particularly well suited for manufacture in molded plastic instead of metal.

According to a feature of the invention, a safety razor comprises a blade platform member, a cap member adapted to clamp a razor blade against the platform, a catch member urged by spring means to a first position in which the catch engages the cap to retain the cap in position on the platform, the catch being movable against the action of the spring means into a second position in which it allows removal of the cap, a detent member which is urged by said spring means into a position of engagement with the catch member to hold the member in its second position, the arrangement being such that the movement of the cap into its clamping position on the platform displaces the detent from its position of engagement, against the action of the said spring means, thereby permitting movement of the catch member into its first position under the action of the said spring means.

Two preferred forms of safety razor each embodying the invention, are described below, by way of example only, with reference to the accompanying drawings, in which:

FIG. 1 is a sectional side elevation of one razor, which is shown in an upright position with the cap uppermost,

FIG. 2 is a sectional plan taken in the line II—II of FIG. 1,

FIG. 3 is a sectional front elevation taken along the line III—III of FIG. 1,

FIG. 4 is a part sectional side elevation of the second form of razor, and

FIG. 5 is a part sectional front elevation taken on the line V—V of FIG. 4.

The razor shown in FIGS. 1 to 3 comprises a body portion 1 which is formed at its upper end with a blade guard 2. The body portion is hollow open at the top and formed with slots 20 and 20a through the side walls which communicate with the hollow interior. A pivot pin 21 is secured at its ends in the front and rear walls of the body portion. A platform member 3 is slidably mounted within the body portion for vertical movement relative thereto. The platform member has a laterally extending slot 5 open at both of its ends, and a vertical slot 6 which communicates at its lower end with the slot 5. The upper end of slot 6 is open at the blade support surface 31 of the platform member. Just below the slot 5 the platform member is divided into front and rear limbs 17, 18 respectively, which are provided on their inner faces with flanges 23, 24, 25 and 26. Near the junction of the limbs and at one side of the platform member there is a tongue 28 which engages in the slot 20 in the adjacent side wall of the body portion. This tongue serves to guide the sliding movement of the platform member relative to the body portion. Elongated slots 17a, 18a are formed in the limbs 17, 18 respectively to allow movement of the platform member relative to the pin 21.

The slot 5 houses a pair of catch members 8 and 9 disposed one adjacent the forward vertical face of the slot and the other adjacent the rear vertical face. The catch members 8, 9 are formed at their inner ends with hook-like projections 10, 11 respectively which bridge the gap

2

between the two members (see FIG. 2), and which are shaped to have upwardly and inwardly sloping surfaces 10A, 11A respectively. The enlarged outer ends of the catch members project beyond the ends of the slot 5 and through the slots in the side walls of body portion 1. The catch members are biased apart by a compression spring 12 working against faces 14 and 15 which are inclined to the vertical. A detent plate 16 is positioned between the catch members 8 and 9 and overlies the spring 12.

A cap 4 is adapted to be detachably secured to the upper end of the platform member and comprises a downwardly extending tongue 7 which is formed with notches whose lower edges 7A and 7B slope inwardly and upwardly as shown in FIG. 3.

A cam disc 19 is rotatably mounted on the pin 21 and lies between the limbs 17, 18 of the platform member. The disc comprises an annular flange 22, whose centre of curvature is offset from the pivotal axis of the disc, and a generally sector shaped portion 27 which projects outwardly through the adjacent slot 20 in the body portion. The flat faces of flange 22 are provided with a number of narrow recesses 29 engageable by corresponding pips 30 on the inner faces of the limbs 17 and 18, and the outer cylindrical surface of the flange 22 engages the flanges 23, 24, 25 and 26.

With the exception of the pin 21 and spring 12, all the component parts of the razor may conveniently be molded from makrolon or some other plastic material.

The razor is illustrated with all its parts assembled together but without a blade in position.

To remove the cap 4 from the razor, the catch members are pressed inwardly by hand against the action of spring 12 so that the hooks 10 and 11 are moved apart, releasing the tongue 7. When the spring is compressed it tends to bow upwardly against the lower face of detent plate 16 and when the hooks 10 and 11 have moved sufficiently far apart, the plate is pushed up by the spring and comes to rest between the hooks to hold them apart. In its upward travel, the plate 16 forces the tongue 7 partially out of the slot 5 and the cap can then be lifted clear of the platform member.

The tongue 7 can then be inserted in the slot in a double-edged razor blade and the cap and blade placed in position on the razor. The tongue is inserted in the slot 6 in the platform member and the cap pressed downwardly. The tongue 7 forces the plate 16 down until that plate clears the hooks 10, 11, thus allowing the catch members to move outwardly, whereupon the hooks engage in the notches in tongue 7. The wedging action exerted by faces 10A and 11A on the edges 7A, 7B respectively ensures that the cap is held firmly in position in the platform member so that the blade is clamped between the lower surface of the cap and the blade supporting surface 31.

The sharp edges of the blade overhang the guard 2 and the gaps A between these edges and the guard can be varied by adjusting the position of the platform member, movement of this member being effected by rotation of the disc 19.

If the disc is rotated in a clockwise direction from its position shown in FIG. 3, the platform member will be moved upwardly (due to the eccentric nature of flange 22), and the gap A will be increased. Conversely, rotation of the cam in the opposite sense will result in the gap A being reduced. The disc is preferably marked with numbers on its outer periphery to give an indication of the adjustment of the position of the platform. The recesses 29 and the cooperating pips serve to retain the disc in certain positions of angular adjustment.

In the second razor shown in FIGS. 4 and 5, the upper part of the razor, including the cap retaining and releasing mechanism, is exactly the same as that of the first described razor, but the lower part of the platform member

3 extend downwardly as a single limb 40, formed with a projection 41. An operating lever 42 is mounted intermediate its ends on the pivot pin 21A and is formed at its upper end with a cam groove 43 in which the projection 41 engages. The lower end of the lever projects through a slot 44 in the bottom wall of the body portion 1 for manual adjustment of the lever.

When the lever is rotated about the pivot pin 21, interaction between the projection 41 and the side faces of the cam groove 43 results in vertical adjustment of the platform member 3 relative to the guard 2 to vary the gap A.

Preferably, numbers are placed on the body portion along the slot 44 to give a visual indication of the adjustment of the platform, and cooperating recesses and projections on the body portion and the lever serve lightly to retain the lever in certain positions of angular adjustment.

Having thus disclosed my invention and described in detail an illustrative embodiment thereof, I claim as new and desire to secure by Letters Patent:

1. A safety razor comprising a blade platform member, a cap member adapted to clamp a razor blade against the platform, a catch member urged by spring means to a first position in which the catch engages the cap to retain the cap in position on the platform, the catch being movable against the action of the spring means into a second position in which it allows removal of the cap, a detent member which is urged by the said spring means into a position of engagement with the catch member to hold the member in its second position, the arrangement being such that the movement of the cap into its clamping position on the platform displaces the detent from its position of engagement against the action of the said spring means, thereby permitting movement of the catch member into its first position under the action of the said spring means.

2. A razor in accordance with claim 1 which includes a

body portion, wherein the cap member is formed with a downwardly projecting tongue having notches in its lateral edges, and comprising a pair of catch members which extend transversely of the body portion in opposite directions, each catch projecting at its outer end through the wall of the body portion and extending inwardly past the tongue and having at its inner end projection for engagement in one of the said notches, the said spring means urging the outer ends of the catches outwardly away from each other, and thereby urging the said projections into engagement with the notches.

3. A razor in accordance with claim 2, wherein the said spring means comprises a coil compression spring which is arranged to buckle when compressed, and the said detent member is disposed adjacent the spring intermediate the ends thereof, the detent being urged into its said position of engagement by the buckling of the spring.

4. A razor in accordance with claim 1, wherein the said springs means comprises a coil compression spring which is arranged to buckle when compressed, and the said detent member is disposed adjacent the spring intermediate the ends thereof, the detent being urged into its said position of engagement by the buckling of the spring.
